United States Patent Office

Des. 226,092
Patented Jan. 23, 1973

226,092

RELIGIOUS MEDAL

Robert R. Salmans, 208 W. Indianapolis,
Wichita, Kans. 67213

Filed Sept. 7, 1971, Ser. No. 178,538

Term of patent 7 years

Int. Cl. D11—03

U.S. Cl. D29—11 C

Fig 1

Fig 2

Fig 3

FIG. 1 is a front view of the religious medal incorporating my new design;

FIG. 2 is a back view; and

FIG. 3 is a longitudinal section taken along line 3—3.

I claim:

The ornamental design for a religious medal, as shown and described.
